AIR VALVE FOR STEAM RADIATORS

Andrew Zarnesky, New York, N. Y.

Application January 7, 1941, Serial No. 373,400

7 Claims. (Cl. 137—122)

This invention relates to new and useful improvements in an air valve for steam radiators.

More particularly, the invention proposes the construction of an air valve which is characterized by a tubular casing having an open bottom end for attachment on a steam radiator, and connected with a tubular member having a solid stem threadedly mounted therein and arranged to operate in a certain way so that the steam radiator may be controlled in several ways.

More particularly, the invention contemplates mounting a handle upon the top of the solid stem, and associating a scale with the handle, to direct turning of the handle, and thus turning of the solid stem to various positions, to obtain various actions of the air valve.

Still further the invention proposes in one position of the handle, that the air valve shall be in a shut off condition preventing the passage of steam into the radiator. With this arrangement there is no necessity of turning off the radiator with the usual valve provided for this purpose. The invention also contemplates a construction which will permit the handle to be placed in various other positions for various other operations of the steam radiator. In another one of the positions specified it is proposed that the air valve operate to check banging. In still another position it is proposed that the air valve operate to prevent the spitting out of water from the air valve.

The invention also proposes other positions which will become clear as this specification proceeds.

Still further the invention contemplates an adaptation of the air valve so that it may be used also on concealed radiators.

Another object is the construction of a device as mentioned which is simple and durable and which may be manufactured and sold at a reasonable cost.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is an elevational view of a steam radiator with an air valve mounted thereon constructed in accordance with this invention.

Fig. 2 is a vertical sectional view drawn on a large scale, of the air valve, per se.

Fig. 3 is a plan view of Fig. 2.

Fig. 4 is a fragmentary elevational view looking in the direction of the line 4—4 of Fig. 2.

Fig. 5 is an inclined vertical sectional view taken on the line 5—5 of Fig. 4.

Fig. 6 is a horizontal sectional view taken on the line 6—6 of Fig. 2.

Fig. 7 is a fragmentary horizontal sectional view taken on the line 7—7 of Fig. 2.

Fig. 8 is a fragmentary horizontal sectional view taken on the line 8—8 of Fig. 2.

Fig. 9 is a sectional view of a window case-ment with a concealed radiator constructed in accordance with a modified form of this invention.

The air valve, in accordance with this invention, is intended to be used in combination with a steam radiator 10 having the usual control valve 11. The air valve 12 is mounted on the side of the radiator 10, in the usual position of the usual air valve. However, the air valve 12 is of an improved construction.

The air valve 12 includes a tubular casing 13 having an open bottom 14 for attachment on the steam radiator, as illustrated in Fig. 1. A tubular member 15 is mounted on the top of the tubular casing 13 and has its top portion internally threaded with threads 16. A combined float and heat responsive device 17 is mounted within the tubular casing 13 for controlling passage of air, steam and water to said tubular member 15. A cap 18 is mounted on the top of the tubular member 15 and has a side opening 19 and a top opening 20.

A solid stem 21 is threadedly mounted within the tubular member 15 and has a bottom valve 22 closing passage from the casing 13 into the member 15. This solid stem 21 also is provided with a frusto-conical top portion 23 within said cap 18. A head portion 24 projects from the frusto-conical top portion 23 and extends through the opening 20 of the cap 18.

A handle 25 is mounted on the head portion 24 by which the stem 21 may be easily turned. A groove 26 is formed in one side of the solid stem 21 and is adapted to be aligned with several openings 27, 28 and 29 formed through the side wall of the tubular member 15. A compressible washer 30 is disposed within the cap 18, and normally is loose within the cap 18 so that there is a tortuous passage around the compressible washer connecting with the discharge opening 19. However, this compressible washer may be compressed when the solid stem 21 is screwed upwards decreasing this passage in proportion to the amount

55 that the stem 21 is screwed upwards.

The top of the cap 18 is imprinted with a scale arranged in an annular area concentric with the axis of the handle 25. This scale has a group of points marked thereon and imprinted with the notations "Off," "On," "S," "A," "K," "B," "W" and "R," as shown in Fig. 3. The compressible washer 30 has a frusto-conical passage engaging upon the frusto-conical portion 23. One wall of this frusto-conical passage is formed with a groove 30' having a small top portion 30^a and a large base portion 30^b as clearly illustrated in Fig. 8. This large base portion 30^b is adapted to be aligned with the top portion of the groove 26 when the stem 23 is unscrewed a certain amount, and more particularly, when the pointer of the handle 25 is on the notation "B" of the scale on the cap 18, as illustrated in Fig. 3.

The valve portion 22 of the solid stem 21 normally engages on a valve seat 31 formed in the tubular member 15. This represents the closed position of the air valve. In this position the top portion of the groove 26 in the solid stem 21 is intimately adjacent the last or topmost thread of the internal threads 16. In this position the groove 26 is immediately to the left side of the opening 27 in the position as illustrated in Fig. 4. This represents the "off" position of the valve. The seat 31 controls a passage 32 through the bottom portion of the tubular member 15. This passage terminates in a double seat 33, 34 which is engaged by a valve 35 of the combined float and heat responsive device 17. A one way valve 36 controls a passage 37 extending through the side of the tubular member 15 along the passage portion 32. This valve 37 is normally urged closed by an expansion spring 38. When the steam within the air valve condenses and a vacuum is produced, the valve 36 automatically is drawn open, so that air is sucked into the air valve to overcome the vacuum.

The combined float and heat responsive device 17 includes a hollow body 40 adapted to float. The valve 35 is mounted on the top of the body. The body 40 has a flexible bottom wall 41. An absorbent material object 42 is disposed within the body 40 and is saturated with some volatile liquid, such as alcohol, or other liquid, capable of great expansion when heated. The float 40 normally rests on an arched partition 43 mounted upon the bottom portion of the tubular casing 13. The float 40 is illustrated in a "hot" position in which the valve 35 is closed.

When the float 40 cools to a normal temperature, the valve 35 will be opened. This valve may also be closed if the tubular casing 13 fills up with water so that the float 40 floats. The arched partition 43 is provided with a plurality of passages 44 through which steam and water from the bottom portion of the tubular casing 13 may pass upwards into the air valve. A tube 46 is mounted through the bottom portion of a cap 47 mounted on the bottom of the tubular casing 13. This cap 47 is provided with the said opening 14.

The tube 46 has a washer 48 fixedly mounted thereon and cooperative with a series of grooves 49 formed internally in the cap 47. A washer 50 is loosely mounted on the top portion of the tube 46 and normally rests on a flange 51 fixedly mounted on the tube 46. This washer 50 is adapted to move upwards against a seat 52 formed within said arched partition 43.

The operation of the device is as follows:

When the handle 24 is turned to the letter "S" on the scale shown in Fig. 3 the solid stem 21

is slightly turned so that it moves up slightly opening the valve 22 and simultaneously aligning the groove 26 with the opening 27. This opening 27 is a very small opening in relation to the size of the openings 28 and 29. In this position of the air valve the entrapped air or steam may escape but very slowly. When the steam radiator is cold and it is desired that it heat quickly, the handle 23 is turned to "A" on the scale shown in Fig. 3. This opens the valve 22 a further distance and aligns the groove 26 with the opening 28. The opening 28 is very large so that the entrapped air in the radiator may quickly escape, bringing the steam into the radiator very rapidly.

The handle 25 may be placed on the letter "K" of the scale shown in Fig. 3 to align the groove 26 with the opening 29. This opening 29 is of an intermediate size, a size between the openings 27 and 28. The radiator is designed so that normally, to maintain a normal quantity of steam in the radiator, the handle 25 should be left on the letter "K."

In the event that the radiator system bangs, either when the radiator is turned on, or at any other time, it is necessary that the handle 25 be placed on "B" of the scale shown in Fig. 3. This disconnects the groove 26 with the several openings 27, 28 and 29, but at this time the top portion of the groove 26 is slightly above the top end of the tubular member 15 and connects with the groove 30'. The steam may now escape up between the conical portion 23 of the stem 21 and the compressible washer 30 and through a tortuous path discharge through the opening 19 in the cap 18. This reduces or completely eliminates the banging action as now there is a cushion to absorb the surging within the radiator which causes the bangs.

If water is spit out through the air valve, the handle 25 should be turned to "W" which will cause the solid stem 21 to rise a sufficient distance so as to slightly compress the compressible washer 30. This cuts down the passage for the discharge of air and water from the opening 19, and consequently cuts down the spitting of the air valve. The handle 25 may be turned to "R" to further compress the compressible washer 30 so as to further cut down the passage towards the opening 19. This further cuts down any spitting and limits escape of steam and air from the air valve to but a minute quantity.

The loose washer 50 upon the tube 46 also acts to cut down the banging of the radiator system. When an increase of pressure due to a bang comes along it strikes the washer 48, which lifts the tube 46 and engages the washer 50 against the seat 52. Furthermore, the increased pressure passing the edges of the washer 48 may also lift the washer 50 against the seat 52.

It is believed that in other respects the operation of the air valve will be clear to those skilled in the art since its construction in these respects is conventional.

In Fig. 9 the air valve 12 is shown connected with an extension stem 55 which connects with the handle 25 thereof. This extension stem has an auxiliary handle 25' on the window sill which words over a disc 18' imprinted with the scale shown on the top of the cap 18. The radiator 10 may be completely controlled by manipulation of the handle 25' on the scale of the washer 18'.

While I have illustrated and described the preferred embodiments of my invention, it is to be understood that I do not limit myself to the precise constructions herein disclosed and the

right is reserved to all changes and modifications coming within the scope of the invention as defined in the appended claims.

Having thus described my invention, what I claim as, new, and desire to secure by United States Letters Patent is:

1. In an air valve for steam radiators having a tubular casing with an open bottom for attachment on a steam radiator and a combined float and heat responsive device for controlling the passage of air, steam and water from said casing, a tubular member having an inlet passage in one end and having its other end portion internally threaded, a cap closing the threaded end portion of said tubular member and having a top opening and a side opening, a solid stem threadedly mounted within said tubular member and having a bottom valve controlling said inlet passage and also having a frusto-conical top portion within said cap and a head extending through the top opening of said cap, a handle mounted on said head for facilitating the turning of said stem, a groove formed in the side of said stem and selectively alignable in several turned positions of said stem with openings formed in the side of said tubular member, and a compressible washer within said cap cooperating with said frusto-conical top portion for decreasing the passage through the side opening in said cap when said stem is screwed upwards.

2. In an air valve for steam radiators having a tubular casing with an open bottom for attachment on a steam radiator and a combined float and heat responsive device for controlling the passage of air, steam and water from said casing, a tubular member having an inlet passage in one end and having its other end portion internally threaded, a cap closing the threaded end portion of said tubular member and having a top opening and a side opening, a solid stem threadedly mounted within said tubular member and having a bottom valve controlling said inlet passage and also having a frusto-conical top portion within said cap and a head extending through the top opening of said cap, a handle mounted on said head for facilitating the turning of said stem, a groove formed in the side of said stem and selectively alignable in several turned positions of said stem with openings formed in the side of said tubular member, and a compressible washer within said cap cooperating with said frusto-conical top portion for decreasing the passage through the side opening in said cap when said stem is screwed upwards, and an air vent valve mounted on one side of said tubular member and communicating with said inlet passage.

3. In an air valve for steam radiators having a tubular casing with an open bottom for attachment on a steam radiator and a combined float and heat responsive device for controlling the passage of air, steam and water from said casing, a tubular member having an inlet passage in one end and having its other end portion internally threaded, a cap closing the threaded end portion of said tubular member and having a top opening and a side opening, a solid stem threadedly mounted within said tubular member and having a bottom valve controlling said inlet passage and also having a frusto-conical top portion within said cap and a head extending through the top opening of said cap, a handle mounted on said head for facilitating the turning of said stem, a groove formed in the side of

said stem and selectively alignable in several turned positions of said stem with openings formed in the side of said tubular member, and a compressible washer within said cap cooperating with said frusto-conical top portion for decreasing the passage through the side opening in said cap when said stem is screwed upwards, and an air vent valve mounted on one side of said tubular member and communicating with said inlet passage, said air vent valve being a spring closed and arranged to be opened by internal suction within said tubular member.

4. In an air valve for steam radiators having a tubular casing with an open bottom for attachment on a steam radiator and a combined float and heat responsive device for controlling the passage of air, steam and water from said casing, a tubular member having an inlet passage in one end and having its other end portion internally threaded, a cap closing the threaded end portion of said tubular member and having a top opening and a side opening, a solid stem threadedly mounted within said tubular member and having a bottom valve controlling said inlet passage and also having a frusto-conical top portion within said cap and a head extending through the top opening of said cap, a handle mounted on said head for facilitating the turning of said stem, a groove formed in the side of said stem and selectively alignable in several turned positions of said stem with openings formed in the side of said tubular member, and a compressible washer within said cap cooperating with said frusto-conical top portion for decreasing the passage through the side opening in said cap when said stem is screwed upwards, and a scale imprinted upon said cap and over which said handle may move.

5. In an air valve for steam radiators having a tubular casing with an open bottom for attachment on a steam radiator and a combined float and heat responsive device for controlling the passage of air, steam and water from said casing, a tubular member having an inlet passage in one end and having its other end portion internally threaded, a cap closing the threaded end portion of said tubular member and having a top opening and a side opening, a solid stem threadedly mounted within said tubular member and having a bottom valve controlling said inlet passage and also having a frusto-conical top portion within said cap and a head extending through the top opening of said cap, a handle mounted on said head for facilitating the turning of said stem, a groove formed in the side of said stem and selectively alignable in several turned positions of said stem with openings formed in the side of said tubular member, and a compressible washer within said cap cooperating with said frusto-conical top portion for decreasing the passage through the side opening in said cap when said stem is screwed upwards, said openings in said tubular member, comprising first a small opening, then a large opening and then an intermediate opening with which said groove may be selectively aligned.

6. In an air valve for steam radiators having a tubular casing with an open bottom for attachment on a steam radiator and a combined float and heat responsive device for controlling the passage of air, steam and water from said casing, a tubular member having an inlet passage in one end and having its other end portion internally threaded, a cap closing the threaded end portion of said tubular member and having a top

opening and a side opening, a solid stem threadedly mounted within said tubular member, and having a bottom valve controlling said inlet passage and also having a frusto-conical top portion within said cap and a head extending through the top opening of said cap, a handle mounted on said head for facilitating the turning of said stem, a groove formed in the side of said stem and selectively alignable in several turned positions of said stem with openings formed in the side of said tubular member, and a compressible washer within said cap cooperating with said frusto-conical top portion for decreasing the passage through the side opening in said cap when said stem is screwed upwards, said compressible washer having a groove adapted to be aligned with the top of the groove in said stem in a certain turned position of said stem.

7. In an air valve for steam radiators having a tubular casing with an open bottom for attachment on a steam radiator and a combined float and heat responsive device for controlling the passage of air, steam and water from said casing,

5 a tubular member having an inlet passage in one end and having its other end portion internally threaded, a cap closing the threaded end portion of said tubular member and having a top opening and a side opening, a solid stem threadedly mounted within said tubular member and having a bottom valve controlling said inlet passage and also having a frusto-conical top portion within said cap and a head extending through the top 10 opening of said cap, a handle mounted on said head for facilitating the turning of said stem, a groove formed in the side of said stem and selectively alignable in several turned positions of said stem with openings formed in the side of said tubular member, and a compressible washer within said cap cooperating with said frusto-conical top portion for decreasing the passage through the side opening in said cap when said stem is screwed upwards, said compressible washer having a frusto-conical opening into which the frusto-conical top of said stem engages.

15 ANDREW ZARNESKY.
